VERTICAL TAKE-OFF AND LANDING AIRCRAFT

Lawrence B. Rellis, 5123 W. Deming Place, Chicago, Ill.

Filed June 9, 1960, Ser. No. 60,904

Term of patent 3½ years

(Cl. D71—1)

FIG. 1 is a top plan view showing my new design for a vertical take-off and landing aircraft with the rotor fans in position for vertical lift;

FIG. 2 is a side elevational view;

FIG. 3 is a bottom plan view;

FIG. 4 is a front elevational view;

FIG. 5 is a rear elevational view with the wheels retracted and the rotor fans in position for forward flight;

FIG. 6 is a side elevational view showing the side opposite that in FIG. 2, with the rotor fans in position for forward flight; and

FIG. 7 is an enlarged, fragmentary, rear perspective view of the tail assembly.

I claim:

The ornamental design for a vertical take-off and landing aircraft, as shown.
